by the United States Atomic Energy Commis-
sion

Application June 14, 1946, Serial No. 676,650

5 Claims. (Cl. 250—41.9)

1

My invention relates in general to electromagnetic isotope separation apparatus having apertured accelerating and decelerating electrodes, and more particularly to apertured accelerating and decelerating electrodes which are so arranged as to reduce flaring in the direction of the magnetic field in the ion beam projected through such electrodes.

An electromagnetic isotope separation apparatus usually comprises a magnetic field, an ionization chamber, apertured accelerating and decelerating electrodes which are arranged to project an ion beam in a direction normal to the magnetic field, a receiver adapted to receive the ion beam at the region of geometrical focus, and an envelope adapted to make it possible to evacuate the space within and surrounding the ionization chamber, the apertured accelerating and decelerating electrodes, and the receiver.

In the operation of the electromagnetic isotope separating apparatus in combination with straight types of apertured accelerating and decelerating electrodes, elongated in the direction of the magnetic field, an appreciable part of the ion beam fails to pass into the receiver due to excessive flaring at the edges of the ion beam as this ion beam is passing through the magnetic field on its path to the receiver. This condition necessitates an increase in the receiver width with the subsequent result that the ratio of scattered to unscattered particles in the receiver is increased. An increase in the number of scattered particles at the receiver end results in a decrease of the enhancement of the final product. It has previously been proposed to eliminate such flaring by curving the adjacent surfaces of the apertured accelerating and decelerating electrodes throughout their entire length, thus creating a curved electrostatic field between said electrodes and causing the ion beam to converge, thereby reducing the required receiver width. This solution of the flaring condition resulted in another problem, due to the concentrated ion beam thus formed being focused on the receiver and producing an unusually hot central portion, which resulted in sputtering of the receiver material along with some sputtering of previously separated ion beam particles which had been deposited thereon.

An object of my invention is to substantially reduce the sputtering of the receiver material and the separated ion beam particles deposited thereon by using apertured accelerating and decelerating electrodes having straight central adjacent faces with curved adjacent faces at their extremi-

2

ties to create an electrostatic field which will focus the ion beam in such a manner as to result in a more equally distributed ion beam at the receiver.

Another object of my invention is to prevent excessive flaring in the edges of the ion beam by curving the faces of the apertured accelerating and decelerating apertures at their extremities so as to create an electrostatic field which will focus the edges of the ion beam towards the center of the receiver.

My invention successfully overcomes the flaring of the ion beam, while substantially reducing the sputtering of the receiver material and the separated ion beam particles deposited thereon, by allowing the central adjacent portions of the apertured accelerating and decelerating electrodes to remain straight while the adjacent extremities of the same apertured accelerating and decelerating electrodes are curved, this extremity curvature being concave toward the ionization chamber for both of the adjacent faces of the apertured accelerating and decelerating electrodes. By localizing the focusing action to the edges of the ion beam, while the central portion of the ion beam remains relatively unaffected, my invention avoids the concentration of the ion beam at the center of the receiver and prevents the excessive sputtering action which normally results therefrom.

These and other important features of my invention will be understood more thoroughly from the following description when taken in conjunction with the accompanying drawing, the single figure of which shows schematically a development of a conventionalized electromagnetic isotope separator incorporating the invention.

With reference to the drawing, positive ions produced in an ion chamber 10 tend to travel towards the aperture of an accelerating electrode 11 in paths approximately normal to equipotential lines 13 which exist between the apertured accelerating electrode 11 and the ion chamber 10. After the positive ions pass through the aperture of the accelerating electrode 11, they find themselves in a decelerating electric field represented by equipotential lines 14 which exist between the apertured accelerating electrode 11 and an apertured decelerating electrode 12. The equipotential lines 14 of the decelerating electric field are curved in the region between the extremities of the adjacent electrode faces due to the extremity curvature of the adjacent faces of the apertured accelerating electrode 11 and the apertured decelerating electrode 12. In the region of the deceler-

ating electric field the ion beam, as represented by a series of ion paths 17, tends to bend away from the normal to the equipotential lines 14, thereby resulting in a focusing action being exerted on the ion paths 17 which exist at the edges of the ion beam as formed by the aggregate ion beam paths. This focusing action results in a reduction of the width of the ion beam and thereby permits the use of an ion receiver 18 having less width than one which is required when straight apertured accelerating and decelerating electrodes are used.

Again referring to the drawing, a detailed discussion of the operational features of the invention and the cooperating elements involved follows:

Positive ions of the material to be separated by the electromagnetic isotope separation apparatus are produced in the ion chamber 10 by bombardment of unseparated material in the vapor state by an electron beam. The electron beam is normally produced by an electrically heated filament, not shown in the drawing, which is maintained at a negative potential with respect to the ion chamber 10. The ion chamber 10 is maintained at a positive potential of approximately 35 kv. with respect to ground potential. The apertured accelerating electrode 11 is maintained at negative potentials of between 15-40 kv. with respect to ground potential, thus placing the apertured accelerating electrode 11 at negative potentials of between 50-75 kv. with respect to the potential of the ion chamber 10. The apertured decelerating electrode 12 is connected to ground potential.

The arrangement of the aforementioned potentials creates an accelerating electric field for positive ions when they are in the region between the ion chamber 10 and the apertured accelerating electrode 11, while it creates a decelerating electric field for the positive ions when they are in the region between the apertured accelerating electrode 11 and the apertured decelerating electrode 12.

The adjacent faces of the ion chamber 10 and the apertured accelerating electrode 11 are approximately parallel to each other and to the direction of a magnetic field 15 which exists throughout an inclosing envelope 16. Therefore, the equipotential lines 13, which represent the accelerating electric field, will be approximately parallel to the direction of the magnetic field 15 and the adjacent faces of the ion chamber 10 and the apertured accelerating electrode 11. Since in an accelerating electric field, charged particles, such as the positive ions created in the ion chamber 10, will tend to traverse paths which are approximately normal to the equipotential lines 13 of the accelerating electric field, the positive ions will therefore assume paths which will be approximately normal to the direction of the magnetic field 15 and the adjacent faces of the ion chamber 10 and the apertured accelerating electrode 11.

The adjacent faces of the apertured accelerating electrode 11 and the apertured decelerating electrode 12 are approximately parallel to each other throughout their entire length, but only their central portion, which is approximately equal to one-third of their entire length, is approximately parallel to the direction of the magnetic field 15. The two extremities of the adjacent faces of the apertured accelerating electrode 11 and the apertured decelerating electrode 12, consisting of approximately one-third of the elec-

trode length for each extremity, are curved lengthwise and concave towards the source of the ion beam for both of said electrodes. The centers for the extremity curvatures fall on a line normal to the electrodes at their mid-points in the direction of the ion chamber 10, and the radii of curvatures required are dependent upon operating voltages, magnetic field strengths, electrode spacings, and upon the degree of focusing desired. The same radius of curvature is used for each electrode. The equipotential lines 14, which represent the decelerating electric field between the apertured accelerating electrode 11 and the apertured decelerating electrode 12, will assume approximately the same configuration in the space between the electrodes as the adjacent surfaces of the apertured accelerating electrode 11 and the apertured decelerating electrode 12; i. e., the equipotential lines 14 will be curved in the horizontal plane at the two extremities between the electrode 11 and the electrode 12 and the central portion will be straight and approximately parallel to the direction of the magnetic field 15. Since, in a decelerating electric field, ion paths which are not initially normal to the equipotential lines 14, tend to bend further away from the normal, the edges of the ion beam, which is formed by the aggregate ion paths 17 from the ion chamber 10, will have a focusing action exerted upon them. The central portion of the ion beam, which is directed approximately normal to the central section of the equipotential lines 14, will be relatively unaffected as to direction of travel while passing between the electrode 11 and the electrode 12.

The focusing effect at the edges of the ion beam due to the curved extremities of the apertured accelerating electrode 11 and the apertured decelerating electrode 12 permits a reduction of the receiver width, which, in turn, results in an increase in the enhancement by virtue of an increase in the ratio of unscattered to scattered particles. The straight central portion of the apertured accelerating electrode 11 and the apertured decelerating electrode 12 results in a more equally distributed beam at the receiver end, thus preventing excessive sputtering of the receiver material and separated particles which may be deposited thereon, which, in turn, means longer receiver life at higher enhancements.

It will be appreciated that the ion beam in traversing the distance between the electrode 12 and the receiver 18 will have followed a circular orbit for approximately 180° in a plane normal to the magnetic field 15.

It will be obvious to those skilled in the art that changes and variations may be made in this apparatus without departing from the spirit of the invention, and therefore the invention herein described is not limited to what is shown in the drawing and described in the specification but only as indicated by the appended claims.

I claim:

1. In electromagnetic isotope separating apparatus, in combination, an evacuated tank, means for establishing a magnetic field traversing said tank in a given direction, an ion source disposed within and at one end of said tank and having an elongated slot for the egress of ions, said slot extending in the direction of the magnetic field, means adjacent said source for accelerating and projecting positive ions emanating from said slot through the magnetic field in a direction normal thereto and in the form of a ribbon beam elongated in the direction of said field, said last

named means comprising two spaced electrodes having slots generally coextensive with the slot of said ion source and also elongated in the direction of the magnetic field, the facing surfaces of said two electrodes being concave toward said ion source at their end portions only, and means for maintaining the outer of said electrodes at a negative potential with respect to said ion source and at a positive potential with respect to said inner electrode, and ion beam receiving means disposed within and at the opposite end of said tank, said receiving means also being elongated in the direction of the magnetic field.

2. Apparatus, as claimed in claim 1, wherein the facing surfaces of said two electrodes each have central sections which are straight and parallel to the magnetic field.

3. Apparatus, as claimed in claim 2, wherein the length of each of said straight central sections is approximately one-third of the entire length of said surfaces.

4. In electromagnetic isotope separating apparatus, in combination, an evacuated tank, means for establishing a magnetic field traversing said tank in a given direction, an ion source disposed within and at one end of said tank and having an elongated slot for the egress of ions, said slot extending in the direction of the magnetic field, means adjacent said source for accelerating and projecting positive ions emanating from said slot through the magnetic field in a direction normal

10

30

thereto and in the form of a ribbon beam elongated in the direction of said field, said last named means comprising a first apertured electrode having an elongated surface facing and paralleling the slot of said ion source and having an opposite surface the central portion of which parallels the slot in said ion source and the end portions of which are cylindrically concave toward said ion source, a second apertured electrode having an elongated surface facing and being a matrix image of said opposite surface of said first electrode and having an opposite surface paralleling the slot in said ion source, and means for maintaining said second electrode at a negative potential with respect to said ion source and at a positive potential with respect to said first electrode, and ion beam receiving means disposed within and at the opposite end of said tank, said receiving means also being elongated in the direction of the magnetic field.

5. Apparatus, as claimed in claim 4, wherein the length of said central portion is approximately one-third the entire length of said opposite surface of said first electrode.
